JOHN HAYS HAMMOND, JR., OF GLOUCESTER, MASSACHUSETTS.

TONE CONTROL OPERABLE SUCCESSIVELY IN A PREDETERMINED MANNER.

Application filed May 5, 1925. Serial No. 23,163.

This invention relates to improvements in musical instruments, and has particular reference to the control of tone shading and musical dynamics.

6 The principal object of the invention is to provide improved means for delicately shading the volume of tone produced by a musical instrument, and thus to permit a more accurate control of the expression imparted to the music being played.

In its broad aspect the present invention relates to the use of a plurality of mechanisms for reducing the volume of musical tone operated from a single device in accordance with the will of an operator.

15 More specifically, there is provided a tone modulator which may be formed of sound insulating material for reducing the musical tone emitted, in combination with additional means, such as a pianissimo action, which further reduces the musical tone emitted, and a single device operating both the tone modulator and the pianissimo action successively at the will of an operator.

20 25 In carrying out the invention in practice I provide a musical instrument of the percussive type, such as a pianoforte, with two separate mechanisms for reducing the tone volume. The tone producing means include a plurality of tuned strings, and there is provided mechanism for initially controlling tone modulators for reducing the volume of sound emitted and subsequently operating a pianissimo action.

30 35 Other objects will appear from the following description taken in connection with the accompanying drawings in which

Figure 1 is a front elevation partly in section of one form of the invention as applied 40 to a grand piano;

Figure 2 is a section taken on the line 2-2 of Figure 1;

Figure 3 is a front elevation partly in section of a modified form of the invention 45 applied to a grand piano;

Figure 4 is a section taken on the line 4-4 of Figure 3; and

Figure 5 is a detailed view partly in section of the pedal mechanism shown in Figures 1 and 3.

50 55 In the form of the invention shown in Figures 1 and 2, the system is shown as applied to a grand piano 10, provided with the usual plurality of strings 11 tuned to the notes of the musical scale and mounted in a framework 12. A conventional piano action

13 is provided for each of the notes of the piano arranged for percussion with the strings tuned to the respective note and operating by means of a key forming part of 60 a usual piano keyboard 14. The instrument includes a so-called pianissimo action for reducing the volume of sound produced by the percussion of the strings 11, and one form of such pianissimo action selected for 65

illustration will now be described. The actions 13 and the keys 14 are mounted in a keybed 15 which is slidably mounted in the framework of the piano so as to be movable with respect to the strings, and is normally 70 maintained in the position shown in Figure 1, by means of a spring 16 positioned in a suitable recess in the casing of the piano. The keybed 15 is provided with a notch 17, cut therein, and there projects into this 75 notch one end of a lever 18 having a pivotal connection at 19 with the stationary framework of the piano 10. The opposite end of the lever 18 is provided with a roller 20 in rolling contact with the cam face of an 80 operating rod 21. The cam face of the operating rod 21 includes a cam projection 22. The lower end of the rod 21 is operatively connected to a control member such as a pedal 23, which may preferably be 85 mounted in a pedal frame 24 depending from the framework of the piano upon rods 25 and 26, and a bracket 27 secured to the framework of the piano under the keyboard. The operating rod 21 is provided with an 90 ear or lug 30 in an intermediate portion thereof, to which is secured one end of a spring 31, the other end of the spring being attached to the frame 24 so as to retract the operating rod 21 into the position shown in 95 the drawing. There are preferably mounted in the base 24, two additional pedals such as 32 and 33, which are operatively connected to two additional operating rods 34 and 35 respectively and to any desired 100 mechanism of the piano such as the sostenuto and loud pedal action.

105 The casing of the piano is formed to include a layer 36 of sound insulating material in the walls thereof, as illustrated, so that the sound produced within the casing may be effectively suppressed and prevented from being emitted. The casing is provided with two series of oppositely disposed controllable apertures, each series being positioned in a 110 plane substantially parallel to the plane of the strings 11 of the piano, and on opposite

sides thereof. There is also provided means for controlling the extent of opening of these apertures, so as to reduce or otherwise control the volume of sound emitted from the 5 casing. The operating means for controlling these apertures includes a roller 40 mounted for rotation upon a lever 41 pivotally secured at 42 to the bracket 27. The roller 40 is in rolling contact with the cam face of the 10 cam 22. The lower or free end of the lever 41 is connected to a link 43 which includes an ear or lug 144 having attached thereto one end of a spring 145, the other end of the spring being secured to the bracket 27, so 15 that the link 43 and the mechanism associated therewith tends normally to assume the position illustrated. The other end of the link 43 is pivotally secured to an arm 44 which is affixed to a vertically extending 20 shaft 45 mounted for rotation in bearings 46, 47 and extending vertically through the casing of the piano. The bearings 46, 47 are secured to the walls of the piano casing and a collar 48 is secured to the shaft 45 immediately above the upper bearing 47 so 25 as to prevent longitudinal movement of the shaft 45 in its bearings. An operating arm 30 50 is secured to the shaft 45 outwardly of and below the casing of the piano and a second operating arm 51 is secured to the shaft 45 outwardly of and above the piano casing. The arms 50 and 51 are connected respectively to a pair of links 52 and 53 the other 35 ends of which are connected to operating rods 54 and 55 respectively. Pivotally connected to the operating rod 54 at spaced points, is a plurality of arms 56 and similarly, pivotally connected to the operating rod 55 at spaced points, there is a plurality 40 of arms 57. Each of the arms 56 and 57 has secured thereto a tone modulator, thus forming two sets of tone modulators 58 and 59 respectively, which are mounted for rotation about their longitudinal axes, in the 45 oppositely disposed apertures respectively, and which control the extent of opening of the apertures so as to regulate the emission of sound therethrough.

In the operation of the form of the invention shown in Figures 1 and 2 when the foot pedal 23 is depressed the rod 21 is elevated and the roller 40 rolls along the inclined surface of the cam 22, and in so doing, rotates the lever 41 in a clockwise direction about 50 the point 42. This causes the link 43 to be moved to the left, thus rotating the arm 44, the shaft 45 and two arms 50 and 51 in a counter-clockwise direction as seen in Figure 2, this will cause the links 52 and 53 to be 55 moved to the right, thus moving the rods 54 and 55 also to the right, which causes the sets of modulators 58 and 59 to be closed.

As the foot pedal 23 is further depressed, the cam shaped projection 22 on the rod 21 60 will engage the roller 20 thus rotating the

arm 18 in a clockwise direction about the point 19, which causes the keybed 15 to be moved to the right against the action of the spring 16, which causes the piano action 13 to be moved so that the hammers do not 70 strike the full number of strings of each note, thus producing the pianissimo effect in the piano.

When the pressure on the foot pedal 23 is released, the rod 21 will move downwardly 75 under the action of the spring 31 and the roller 20 will move down the face of the cam 22, thus allowing the keybed 15 to be moved to the left under the action of the spring 16, thus taking off the soft pedal action of the 80 piano. As the rod 21 continues to move downwardly the roller 40 will roll down the face of the cam 22, thus causing the modulators to be opened under the action of the 85 spring 145.

It is thus seen that when the foot pedal is depressed, the modulators will be gradually closed and then the pianissimo action will be put on and when the foot pedal is released the soft pedal action will first be thrown off 90 and then the modulators will be gradually 95 opened.

In the modified form of the invention shown in Figures 3, 4 and 5, the system is shown as applied to a grand piano 70, which is provided with the usual keybed 71 slidably mounted in the frame of the piano and held in the position shown in Figure 3 by means of a spring 72. The keybed 71 is provided with a notch 73 into which fits one end of a bell-crank 74 which is mounted for rotation upon a pivot 75 which is secured to the framework of the piano 70. The other end of the bell-crank 74 is in line with a rod 76 which is slidably mounted in a bracket 77 100 supported by the framework of the piano. At its lower end the rod 76 rests upon the rear end of a pedal 78 which is pivoted at 80 in a block 81 which is supported from the bracket 77 by means of two rods 82 and 83. The rod 76 is provided with a lug 84 to which is secured one end of a spring 85 the other end of which is fastened to the block 81. Mounted in the block 81 are two additional pedals 86 and 87 which operate two 110 rods 90 and 91 which control the sostenuto and loud pedal action of the piano in a well known manner.

Secured to the shaft 76 is a collar 92 which prevents it being pulled below a certain predetermined height. Secured to the upper end of the rod 76 is a collar 93 upon which rests a member 94 which is rotatably mounted upon the rod 76. Connected to one end of the member 94 by means of a ball and socket joint is a link 95 the other end of which is connected also by a ball and socket joint to a bell-crank 96 which is pivoted at 97 to the framework of the piano and is provided with a handle 98.

Cooperating with the other end of the member 94 is a bell-crank 100 which is pivoted at 101 to the bracket 77. At its lower end the bell-crank 100 is provided with a hole 6 through which slides a rod 102 to which is secured a collar 103. To the end of the rod 102 is fastened a second collar 104 between which and the bell-crank 100 is a spring 105. The rod 102 is provided with a lug 106 10 to which is connected one end of a spring 107 the other end of which is secured to a bracket 108 mounted upon the framework of the piano. The other end of the rod 102 is connected to an arm 110 which is rigidly secured 15 to one end of a shaft 111. Rigidly secured to the shaft 111 is an arm 112 to the end of which is connected a link 113 the other end of which is connected to a rod 114. To the rod 114 is pivoted a plurality 20 of arms 115 which are mounted upon an equal number of tone modulators 116 mounted for rotation about their longitudinal axes in the framework of the piano 70. The upper end of the shaft 111 operates a tone 25 modulator mechanism similar to that described in connection with Figures 1 and 2.

In the operation of the modified form of the invention shown in Figures 3, 4 and 5, when the pedal 78 is depressed the rod 76 30 will be elevated and the member 94 engaging the bell-crank 100 will cause it to be rotated in a counter-clockwise direction, thus moving its lower end to the right which will act upon the spring 105 causing it to push 35 the collar 104 to the right, thereby moving the rod 102 to the right. This causes the arm 110, the shaft 111 and the arm 112 to be rotated in a counter-clockwise direction, thus moving the link 113 and the rod 114 to 40 the right which causes the tone modulators 116 to be closed. A similar action takes place with the tone modulators on the top of the piano. When the tone modulators have become entirely closed and the foot 45 pedal 78 is depressed further, the bell-crank 100 will continue to be rotated and will compress the spring 105. At the same time the end of the rod 76 will engage the bell-crank 74, thus rotating it in a clockwise direction 50 about the pivot 75. This will cause the upper end of this bell-crank to be moved to the right, thus moving the keybed 71 to the right and throwing on the pianissimo action of the piano in a well-known manner. 55 If it is desired to operate the soft pedal action entirely independent of the tone modulators leaving them wide open, the handle 98 is moved to the right thereby rotating the bell-crank 96 in a clockwise direction 60 about the pivot 97 which by means of the link 95 causes the member 94 to be rotated in a counter-clockwise direction on the shaft 76. This will cause the member 94 to be moved out of alignment with the bell-crank 100 so that when the pedal 78 is 65

depressed and the rod 76 elevated it will not operate the bell-crank 100 but will only engage the bell-crank 74. The tone modulators 116 will therefore remain in the open position as shown, while the pianissimo action will be thrown on as previously described. 70

The invention upon which this application is based is broader than the specific embodiment shown and described for the 75 purpose of illustrating at least one of the ways in which it may be employed. The scope of the invention is therefore to be understood as not being limited by the present specific description. I intend no limitations 80 other than those imposed by the claims.

What I claim is:

1. A tone modulating system for a piano-forte, comprising a tone modulating pedal, means effective for suppressing the musical 85 sound emitted from the pianoforte, a pianissimo action for controlling the initial volume of musical sound produced by the strings of the pianoforte, and means operatively interconnecting the pedal, the sound 90 suppressing means and the pianissimo action arranged so that actuation of the pedal first operates the sound suppressing means and thereafter the pianissimo action.

2. A tone control system for a piano, comprising a pedal, sound suppressing means operable upon the initial movement of the pedal, and means for controlling the volume of musical sound initially produced by the strings of the piano operable upon additional movement of the pedal. 95

3. A tone control system for a piano, comprising a pedal, sound suppressing means operable upon the initial movement of the pedal, and a pianissimo action for controlling the volume of musical sound initially produced by the strings of the piano operable upon additional movement of the pedal. 105

4. In a musical instrument, a plurality of tuned strings for producing musical tones, a casing including substantially sound proof material around said strings, percussive means within the casing and movable with respect to the strings to cause a striking contact with the strings, keys for initiating the striking movement of the percussive means, means to adjust said percussive means with respect to the strings, a plurality of modulators positioned in the casing for controlling the volume of musical sound emitted 110 therefrom, and a pedal operatively connected to impart movement initially to said modulators and to impart movement subsequently to the adjusting means. 115

5. In a musical instrument having a percussive action for producing musical sound, a pianissimo mechanism for controlling said percussive action to vary the amplitude of sound produced thereby, a pedal for controlling said pianissimo mechanism, a tone 120 125 130

modulator for varying the volume of musical sound emitted from the instrument, and means interconnecting said modulator and said pedal for actuating said modulator in advance of said pianissimo action.

6. In a musical instrument of the percussive type, a plurality of hammers, strings arranged to be set into vibration by impact thereon of said hammers, a plurality of keys for actuating said hammers respectively, a plurality of tone modulators for varying the intensity of musical sound emitted from the instrument, means for variably positioning the hammers with respect to the strings to modify the intensity of sound produced by said strings upon the impact of the hammers thereon, and means initially effective for operating the tone modulators and for subsequently operating the hammer positioning means.

7. In a musical instrument of the percussive type, the combination of a casing having oppositely disposed, controllable apertures, means positioned within the casing for producing musical tones by percussion, a manual for actuating said percussive means, means for controlling the extent of opening of said apertures for varying the intensity of musical sound emitted from the instrument, means acting on said percussion means to modify the intensity of sound produced thereby, and means connected to actuate said opening control means initially and said intensity modifying means subsequently.

8. In a musical instrument of the percussive type, a plurality of hammers, strings arranged to be set into vibration by impact thereon of said hammers, a plurality of keys for actuating said hammers respectively, a plurality of tone modulators for varying the intensity of musical sound emitted from the instrument, means for variably positioning said hammers with respect to said strings to modify the intensity of musical sound produced by said strings by the impact of the hammers, a sound intensity control pedal, and means operatively connecting said pedal to said tone modulators and said hammer positioning means effective initially for operating the tone modulators and effective thereafter for operating said hammer positioning means.

9. In a musical instrument having a percussive action for producing musical sound, a tone modulator for varying the volume of musical sound emitted from the instrument, a pianissimo mechanism for the percussive action to vary the amplitude of musical

sound produced thereby, a pedal operative initially to control the modulator to regulate the volume of musical sound emitted from the instrument, and means interconnecting said pedal and said pianissimo mechanism ineffective for operating the pianissimo mechanism until the modulator has been actuated.

10. A tone modulating system for a pianoforte comprising a tone modulating pedal, means effective for suppressing the musical sound emitted from the pianoforte, a pianissimo action for controlling the initial volume of musical sound produced by the strings of the pianoforte and means operatively interconnecting the pedal, the sound suppressing means and the pianissimo action arranged to render said pedal ineffective for actuating said sound suppressing means.

11. A tone control system for a piano comprising a pedal, sound suppressing means operable upon movement of the pedal, means independently operable upon movement of the pedal for controlling the volume of musical sound initially produced by the strings of the piano and means for rendering said sound suppressing means inactive with respect to movement of the pedal.

12. A tone control system for a piano comprising a pedal, sound suppressing means operable upon movement of the pedal, a pianissimo action for controlling the volume of musical sound initially produced by the strings of the piano, and means for rendering said sound suppressing means inactive with respect to said pedal.

13. In a musical instrument, a plurality of tuned strings for producing musical tones a casing including substantially soundproof material around said strings, percussive means within the casing and movable with respect to the strings to cause a striking contact with the strings, keys for initiating the striking movement of the percussive means, means to adjust said percussive means with respect to the strings, a plurality of modulators positioned within the casing for controlling the volume of musical sound emitted therefrom, a pedal operatively connected to impart movement to said modulators and to said adjusting means and a manually controlled device for rendering said modulators inactive with respect to said pedal.

Signed at New York city in the county of New York and State of New York this 4th day of May, A. D. 1925.

JOHN HAYS HAMMOND, Jr.
